AIR CUSHION VEHICLE

Alfred G. Anderson, Bethesda, Philip W. Jackson, Jr.,
Silver Spring, and Melville W. Beardsley, Severna Park,
Md., assignors to National Research Associates, Inc.,
College Park, Md., a corporation of Maryland

Application August 3, 1959, Serial No. 57,056

Term of patent 14 years

(Cl. D71—1)

FIG. 1.

FIG. 2.

FIG. 3.

Des. 187,896

PAGE 2

FIG. 4.

FIG. 5.

Fig. 1 is a perspective view of an air cushion vehicle showing my new design;
Fig. 2 is a front elevational view thereof;
Fig. 3 is a rear elevational view thereof;
Fig. 4 is a top plan view of an air cushion vehicle; and
Fig. 5 is a side elevational view thereof.

What is claimed is:

The ornamental design for an air cushion vehicle, as shown.
